HINGING ARRANGEMENT

Charles H. Bayer, Wynnewood, Pa., assignor to
General Electric Company, a corporation of
New York

Application June 18, 1947, Serial No. 755,315

6 Claims. (Cl. 220—32)

1

My invention relates to improvements in hinging arrangements whereby one member can be mounted on a corner of another for swinging movement relatively thereto, and more particularly my invention relates to improvements for hinging covers on the corners of terminal boards having a base and a plurality of spaced walls extending therefrom to provide individual terminal mounting spaces which for safety and other purposes have to be covered normally and yet must be readily accessible for inspection and wiring purposes.

Terminal boards, or blocks as they often are called, usually comprise a base from which arise a plurality of parallel walls defining spaces in which terminals are mounted on the base. These blocks are usually made of molded insulating material, and the spaces are open at the ends for wires connected to the terminals. The spaces may in some cases be open at the top, but, if so, dust and dirt readily collect on the terminals and the possibility of short circuits in consequence of falling objects, such as tools and the like, of conducting material is too great to be neglected. Covers have been provided, but these are mounted on the top surfaces of the walls by screws. Such structure is time consuming in labor and cost not only of manufacture but in working on the terminal boards and especially so since boards of different sizes usually appear in the same installation. In consequence of which, covers get mixed or misplaced, screws lost, etc. Because of high unit labor costs especially today, common hinge mountings are too costly for consideration not only from the standpoint of the hinge itself but also the preparation of the terminal board to adapt the hinge thereto. Moreover, any hinge mounting of a metallic character must involve the minimum amount of material not only from the standpoint of cost but also to minimize the probability of short circuits. Moreover, the satisfactory hinge mounting should embody the minimum amount of work in preparation of the cover and the block, and it should be possible to assemble the mounting without the use of tools or at least with a tool no more complicated than a simple screw driver.

An object of my invention is to provide an improved corner hinging arrangement which while not so limited in its application is particularly adapted for use with thin insulating covers for terminal blocks. Another object of my invention is to provide an improved corner hinging ar-

2

angement which is economical, compact, electrically safe, simple and easy to install, and readily adaptable to terminal blocks of different sizes regardless of the number of terminal spaces. A further object of my invention is to provide an improved corner hinge biased mounting which requires no screws, rivets, or the like and uses a minimum amount of space and material and yet is sufficiently rugged and durable for its intended use. These and other objects of my invention will hereinafter appear in more detail.

My invention will be better understood from the following description when considered in connection with the accompanying sheet of drawings, and its scope will be pointed out in the appended claims.

In the accompanying sheet of drawings, Fig. 1 illustrates a hinging arrangement embodying my invention as applied to a terminal block and cover shown in plan view with the cover open; Fig. 2 is a side view of the terminal block and cover shown in Fig. 1 with the cover shown in the closed position; Fig. 3 is an end elevation of the terminal block and cover shown in Fig. 1; Fig. 4 is a plan view of a hinge element embodying my invention; Fig. 5a is a partial sectional elevation on the line 5—5 of Fig. 1 assuming the cover closed and showing the hinge element of Fig. 4 partially installed; and Fig. 5b is a partial sectional elevation on the line 5—5 of Fig. 1 assuming the cover closed and showing the hinge element fully installed.

For the purpose of illustrating my invention, I have shown an embodiment thereof in a terminal board having a base 1 and a plurality of spaced walls such as end walls 2 and intermediate walls 3 extending from the base to provide spaces for connectors 4 suitably secured to the base as by rivet inserts 5 and provided with conductor clamping means such as washer headed screws 6. As shown, each of the end walls 2 is provided with a recessed portion 7 for the reception of suitable fastening means such as a screw 8 through the base 1 for securing the terminal board to a switchboard or other structure 9, as shown in Fig. 3. Preferably the terminal boards are of molded insulating material, and the number of connector spaces may vary from four to twelve or more to take care of as many circuits.

For covering the spaces between the walls at the outer edges thereof, a cover 10 is provided, and for swinging movement relatively to the terminal block this cover is mounted thereon

by an aligned corner mounting hinge arrangement embodying my invention so that the cover can be swung over and away from the outer edges of the walls to cover and uncover the spaces therebetween. This hinging arrangement, in accordance with my invention, embodies a double hook hinge element 11 which, as shown in full in Figs. 4, 5a and 5b, is generally U-shaped to form the main hinge hook with one of its legs bent inwardly at its free end to provide a re-entrant hook portion 12 extending substantially perpendicular to the leg 13. The double hook hinge element 11 is preferably made of resilient material such as spring wire so shaped that prior to installation on the corner of the terminal block the legs 13 and 14 converge slightly from the bight 15, as shown in Fig. 4. Preferably the legs are of unequal length, the leg 14 being the shorter.

Further in accordance with my invention, the hinge elements respectively extend through spaced openings 16 in the cover 10 near one outer edge thereof and of materially greater area than the cross-sectional area of the hinge element with the shorter legs 14 respectively extending with a snug fit into holes 17 respectively provided in the outer side adjacent the corner of two of the walls such, for example, as the end walls 2, as shown more clearly in Fig. 5a, and respectively registering with the openings in the cover and the bent portions 12 of the legs 13 respectively extending with a snug fit into holes 18 respectively provided in the adjacent side that forms the aligned corners of the walls 2, all as shown in Fig. 5b.

In mounting the hinge element 11, the cover 10 is placed in the closed position on the top edges of the walls 2 and 3 of the terminal block with the cover openings 16 registering with the holes 17 adjacent the aligned corner of the walls 2, as shown in Fig. 5a. The short end 14 of the hinge element is then inserted through the opening 16 in the cover into the hole 17 in the end wall 2, as shown in Fig. 5a, with the bent end 12 bearing against the adjacent side that forms the corner of the wall 2. As the short end 14 is pushed further into the hole 17, the bent portion 12 of the longer leg registers with the hole 18 provided in the adjacent side that forms the corner of the wall 2. This bent end 12 may then be pushed into the hole 18 and the assembly is completed, as shown in Fig. 5b. To facilitate the assembly and to assure that the corner hinge element 11 remains in place, this element is so shaped or formed originally that the legs 13 and 14 converge from the bight 15, as shown more clearly in Fig. 4. In this way, the resilience of the element 11 maintains the bent end 12 in the hole 18. Inasmuch as the holes 17 and 18 are substantially perpendicular to each other in the adjacent converging sides that form a corner of wall 2, both lateral and upward movements of the hinge element 11 are prevented, as long as the bent portion 12 remains in the hole 18. From the foregoing, it will be obvious that this assembly can be very simply and readily performed with a tool as simple as a screw driver. For maintaining the cover in the closed position, there are provided suitable means such as captive thumb screws 19 which screw into threaded holes or threaded inserts 20 molded in the walls 2 of the block.

While I have shown and described my invention in considerable detail, I do not desire to be limited to the exact arrangements shown, but seek to cover in the appended claims all those modifica-

tions that fall within the true spirit and scope of my invention.

What I claim as new and desire to secure by Letters Patent of the United States:

- 5 1. An arrangement for hinging a member on a corner of a support comprising at least one generally U-shaped hinge element having legs of unequal length and a portion of the free end of the longer leg bent inwardly at a predetermined angle thereto and said element extending through an opening provided in said member and of materially greater area than the cross-sectional area of the shorter leg with the shorter leg extending with a snug fit into a hole provided in one side of the corner of said support and registering with the opening in said member and the bent portion of said longer leg extending with a snug fit into a hole provided in the adjacent side of the corner of said support at approximately said predetermined angle to and adjacent the hole in the support into which the shorter leg extends.
- 10 2. An arrangement for hinging a member on a support having corners in alignment comprising two generally U-shaped hinge elements, one of the legs of each of said elements having its free end bent inwardly at a predetermined angle to the leg and said elements respectively extending through spaced openings provided in said member and of materially greater area than the cross-sectional area of the other legs with the other legs respectively extending with a snug fit into holes respectively provided in one side of the aligned corner of said support and respectively registering with the openings in said member and the bent portions of said first-mentioned legs respectively extending with a snug fit into holes respectively provided in the adjacent side of the corners of said support at approximately said predetermined angle to and adjacent the holes in the support into which said other legs extend.
- 15 3. An arrangement for hinging a member on a support having adjacent sides forming a corner comprising at least one generally U-shaped resilient hinge element having legs of unequal length and a portion of the free end of the longer leg bent inwardly at a predetermined angle thereto and said element extending through an opening provided in said member and of materially greater area than the cross-sectional area of the shorter leg with the shorter leg extending with a snug fit into a hole provided in one side of the corner of said support and registering with the opening in said member and the bent portion of said longer leg extending with a snug fit into a hole provided in the adjacent side of the corner of said support at approximately said predetermined angle to and adjacent the hole in the support into which the shorter leg extends, said element being so shaped that the legs thereof converge from the bight of the element until insertion of the end portions of the legs in the holes in the adjacent sides of the corner of said support.
- 20 4. In a cover hinging arrangement for a terminal board having a base and a plurality of spaced walls extending therefrom and provided with at least one corner, a cover and corner mounted means for pivotally mounting said cover for movement over and away from the outer edges of said walls to cover and uncover the spaces therebetween comprising at least one generally U-shaped hinge element, one of the legs of said element having its free end bent inwardly at a predetermined angle to the leg and said element

extending through an opening provided in said cover near one edge thereof and of materially greater area than the cross-sectional area of said other leg with the other leg extending with a snug fit into a hole provided in the outer side of the corner of one of said walls and registering with the opening in said cover and the bent portion of said one leg extending with a snug fit into a hole provided in the adjacent side of the corner of said wall.

5. In a cover arrangement for a terminal board having a base and a plurality of spaced walls extending therefrom and provided with corners in alignment, a cover, and corner mounted means for pivotally mounting said cover for movement over and away from the outer edges of said walls to cover and uncover the spaces therebetween comprising two U-shaped hinge elements each having one leg longer than the other and a portion of the free end of the longer leg bent inwardly at a predetermined angle thereto, said elements respectively extending through spaced openings provided in the cover near one edge thereof and of materially greater area than the cross-sectional area of the shorter leg with the shorter legs respectively extending with a snug fit into holes respectively provided in the outer side adjacent the corners of two of said walls and respectively registering with the openings in said cover and the bent portions of said longer legs respectively extending with a snug fit into holes respectively provided in the adjacent side forming the aligned corners of said two walls.

6. In a cover arrangement for a terminal board having a base and a plurality of spaced walls extending therefrom and provided with corners in alignment, a cover, and corner mounting means for pivotally mounting said cover for

movement over and away from the outer edges of said walls to cover and uncover the spaces therebetween comprising two generally U-shaped resilient wire hinge elements each having one leg longer than the other and a portion of the free end of the longer leg bent inwardly at a predetermined angle thereto, said elements respectively extending through spaced openings provided in the cover near one edge thereof and of materially greater area than the cross-sectional area of the shorter leg with the shorter legs further respectively extending with a snug fit into holes respectively provided in the outer side adjacent the corners of two of said walls and respectively registering with the openings in said cover and the bent portions of said longer legs respectively extending with a snug fit into holes respectively provided in the adjacent side forming the aligned corners of said two walls, each of said elements being so shaped that the legs thereof converge from the bight of the element until insertion of the end portions of the legs in the holes in said adjacent sides of said corners.
